INSULATING PANEL FOR BUILDING WALLS

George E. Brierly, Detroit, Mich.

Application April 28, 1938, Serial No. 204,888

4 Claims. (Cl. 189—85)

This invention relates to insulating panels or blocks for the interior or the exterior faces of building walls, and the principal object is to provide a block formed of an inexpensive metallic container and an insulating element secured therein which may be held in courses as with various building blocks or brick, or in the manner of tile on an interior wall surface, in either of which the metallic casing is exposed to view.

10 It is further an object and feature of the invention to provide a metallic casing of a rectangular form having side walls and a bottom, the opposite face being open to receive an insulating member which may be secured therein in any approved manner as by cementing the same in place or by forming the casing subsequent to the placement of the insulating material in a manner to secure the same therein.

It is further a feature and object of the invention to provide an insulating block or tile such as above described in which the side walls of the metallic container are provided with projections to align with similar projections of the adjacent block or tile and thus providing a uniform space 25 between adjacent blocks for a plastic or cementitious material and in which arrangement the projections are so positioned that a block will readily be erected in association with a half size block and a quarter size block with the projections of the major size block fitting the projections on the blocks of the other faces.

These and various other objects and novel features of the invention are hereinafter more fully described and claimed, and the preferred form of 35 a block or tile embodying my invention is shown in the accompanying drawing in which—

Fig. 1 is a plan view of the outer face of a block or tile in association with a second block or tile, the drawing being partly broken away to show the inner insulating element.

Fig. 2 is an edge elevation thereof.

Fig. 3 is a plan view of a portion of the block showing the opposite face from that shown in Fig. 1.

45 Fig. 4 is an enlarged detail showing one form of a projecting lug.

Fig. 5 is a sectional view taken on line 5—5 of Fig. 4.

Fig. 6 is an elevation showing another form of 50 projecting lug.

Fig. 7 is a section taken on line 7—7 of Fig. 6.

Fig. 8 is an elevation showing various sizes of the blocks that may be laid with the projections of each of the blocks aligning with and engaging 55 similar projections of other blocks.

Fig. 9 is a perspective view showing my improved block or tile applied directly to the sheathing of a wall element.

The block may be made of various sizes and of various thicknesses but, due to the insulating character of the block, need not be very thick from face to face and may be quite thin where used as a tile for mounting on the interior of a wall.

10 In its preferred form, the block consists of a rectangular metal shell as indicated at 1 and there shown as square in form. As will be observed from Fig. 2 particularly, the shell 1 has a metal bottom 2 and side walls 3 and an open face opposite the wall 2. In this pan-like form of shell is placed an insulating material indicated at 4 which may be of any approved form but preferably of a self-sustaining type such as the well known commercial Celotex or other types of insulating board. The insulating member 4 is secured in the shell and may be secured in several ways as, for instance, by coating the inner face of the shell and/or the edges and one face of the insulating element with pitch which becomes subsequently very hard and the manner of attachment of the block or panel to a wall is preferably by means of cement applied to the outer exposed face of the insulator member 4 as is indicated at 5 in Figs. 1 to 7 inclusive. The insulating element may also be secured in place as by inturning an edge 8 or portions of the edge of the side walls of the shell 1 over the peripheral edge of the insulating member as shown in Figs. 5 and 7. For securing the panel or block in position, a cementitious material may be applied to the exposed face of the 20 insulating element in any approved manner whereby the same may be secured to a surface, as for instance the sheathing 7 of the wall, shown in Fig. 2.

25 A feature of the invention is involved in the provision of the outstanding lugs about the periphery of the shell. These lugs may be pressed out in forming the shell as is indicated in Figs. 1 and 5 or may be provided, as indicated at 10, by means of a metal lug secured, as by welding, to 30 the shell after the manner indicated in Figs. 6 and 7. The form of the lugs in outline is not of particular moment but the shell, subsequent to the formation and provision of the lugs, is submitted to a grinding operation to true the outer faces of the lug and to provide a block of a definite overall size which would be a standard size or multiples or divisions of a standard size so that the blocks, when laid, are spaced accurately to provide uniform interstices between the blocks 35 40 45 50 55

and thus do not require odd sizes of blocks in the formation of a wall other than the required multiples or divisions of the block. This will be more fully understood from Figs. 8 where is shown a 5 major size block at 11 having the lugs 9, 10 or other form so spaced about the periphery as to match lugs of blocks of a half size indicated at 12 and a quarter size as indicated at 13, 13. It will be observed from this view that, by properly spacing the lugs on a major size block and on the 10 divisional sizes, the lugs of several adjacent sizes of the blocks align with the lugs of the respective lugs of contiguous blocks or panels. Thus, by forming the shell with its projecting lugs accurately 15 surfaced to provide an overall length and width of block, a wall may be uniformly laid to fit any length or height of wall surface that is a multiple of the major block size.

The lugs have three functions—namely, to determine 20 the overall dimension; to space the blocks or panels a predetermined distance apart to provide for a uniform spacing of the blocks in which a plastic or cementitious material may be forced, and to sustain such plastic from sagging, particularly 25 in vertical interstices between blocks which sometimes under a hot sun may tend to soften and sag.

As previously stated, the faces of the lugs are to be ground to provide a block of a standard 30 overall size and in divisions or multiples of one of the sizes. For the best results, the faces of the lugs are to be ground to a true plane surface, the lugs on one side edge being at a right angle to the adjacent side edges and parallel with the 35 plane surfaces of the opposite parallel side of the block. This insures not only the proper spacing of the laid blocks but tends to position the series of blocks with their faces in substantially the same plane or so nearly so as not to be readily observed. An essential characteristic of the 40 invention is therefore involved in thus providing the spaced lugs which, in contiguous blocks, are in surface contact to thereby effect a true parallelism of the surfaces of the outer faces of the 45 panels or blocks and any inaccuracies in the wall surface to which they are to be applied may be compensated for by the use of an adhesive in greater or less quantity on the inner faces of the panels.

50 The blocks or panels are applied to a wall surface by placing a sufficient amount of cementitious material at various points on the surface of the insulating element sufficient to securely hold the panel or tile in place on a supporting surface as, for instance, the sheathing 7 of Fig. 9.

The outer face of the metal panel may be embossed if desired, as indicated at 14 in Fig. 8 which is illustrative only of one form of embossing, it being understood that various designs may be provided by embossing the sheet metal, and it is to be observed that it is the metal surface that is exposed to atmosphere, either of a room or outside atmosphere and the metal of which the shell is made may be of any desired composition or character as, for instance, stainless steel, copper, brass or other composition and even may be treated to provide a color effect.

The drawing has shown the device as being of 70 rectangular form and this is the usual form but in all wall surfaces where the block may be applied, there are portions of such surface other than rectangular, and it is to be understood that changes in form of the block to fit a particular area are within the spirit and scope of this 75 invention, a feature of which is in the provision

of lugs on peripheral wall of the block to engage lugs of an adjacent block.

From the foregoing description, it is believed 5 evident that the various objects and features of the invention are attained by the structure described; that the block is of an inexpensive character, being formed of very light gauge metal which becomes a retainer for an insulating element but serves to protect such element from weather conditions and may furnish either a dull 10 or a bright surface as may be desired in various types of structures and for various locations on the interior walls of a building, and it is also to be understood that various changes may be made in the form of the structure (which may be other than rectangular as shown) without departing from the spirit and scope of the invention as set forth in the appended claims. 15

Having thus fully described my invention, its 20 utility and mode of operation, what I claim and desire to secure by Letters Patent of the United States is—

1. An insulating block for the surfacing of building walls comprising a sheet metal shell of 25 rectangular form having peripheral walls at a right angle to the sheet and providing a shell open on one side, a preformed insulating element secured in the shell, the thickness of which is approximately equal to the depth of the peripheral walls, an adhesive material applied to the 30 exposed face of the insulating element for securing the block on a wall and means formed integrally with the side walls for spacing laid blocks in a predetermined spaced relation providing an interstice for cementitious material. 35

2. An insulating block for the surfacing of building walls comprising a sheet metal shell having a rectangular base, the edges thereof being turned inward to provide side walls, the said side walls having portions thereof struck outwardly 40 to provide spacing lugs to maintain laid blocks in a predetermined spaced relation to provide for a cementitious filler, and a preformed insulating element of peripheral form corresponding to the shell and fitting within the side walls, 45 the thickness of the insulating block being substantially equal to the interior depth of the side walls, and an adhesive material on the exposed face of the insulating element for securing this block on a wall. 50

3. A series of insulating blocks for the surfacing of insulating walls each comprising a sheet metal shell of rectangular form having side walls and a base, a sheet of preformed insulating material cementitiously secured in the shell with 55 the outer face thereof substantially flush with the edges of the side walls, the shells being of several sizes in multiple of a minimum size and each having portions of the side walls outpressed to form lugs, the spacing of which is such that 60 blocks of different sizes may be laid in contact one with the other with the lugs on each of the blocks in engagement with the lugs on the contiguous blocks to thereby provide a uniform spacing therebetween for a cementitious material, and an adhesive material on the exposed face of the insulating element for securing the blocks in place on the wall with the metal presented to view. 65

4. A series of insulating blocks for the surfacing of building walls, each comprising a sheet metal shell having a base of desired peripheral form and integral side walls providing a shell open on one side, a sheet of preformed insulating material cementitiously secured in the shell 70 75

with the outer face thereof substantially flush with the edges of the side walls, the side walls of each of the blocks being out-pressed to form lugs, the spacing of which is such that blocks of different sizes may be laid in contact with the lugs of contiguous blocks to provide a uni-

form spacing thereof for cementitious material, an adhesive material on the exposed face of each of the insulating elements for securing the same in place on the wall with the base of the metal shell presented to view.
